United States Patent Office

Des. 205,514

Patented August 16, 1966

205,514

EASEL

Harold Rubin, New Milford, N.J., assignor to Testrite
Instrument Co., Inc., Newark, N.J., a corporation of
New York

Filed Sept. 13, 1965, Ser. No. 86,995

Term of patent 14 years

(Cl. D29—20)

FIG. 1

FIG. 2

FIG. 1 is a front and right side perspective view of an easel embodying my new design; and

FIG. 2 is a rear and left side perspective view thereof.
I claim:

The ornamental design for an easel, as shown.
